Primary Examiner — Susan Moon Lee(74) Attorney, Agent, or Firm — Klarquist Sparkman, LLP(57) CLAIM

The ornamental design for a pet bowl, as shown and described.

DESCRIPTION

FIG. 1 is a front perspective view of the new design for a pet bowl.

FIG. 2 is a top plan view of the new design of FIG. 1.
